ASH REMOVAL AND SIFTING DEVICE

Albert Delean, Kirkland Lake, Ontario, Canada

Application March 13, 1944, Serial No. 526,297

2 Claims. (Cl. 126—244)

The present invention pertains to a novel ash sifter applied to a furnace.

The principal object of the invention is to provide such a device whereby ashes may be sifted without being manually carried or wheeled away from the furnace. Another object is to enable the sifting operation to be performed without creating dust outside the furnace.

Still another object is to incorporate the draft passage in the sifting apparatus which otherwise would obstruct the passage.

These objects are accomplished by providing a trough with a screw conveyor therein beneath the grate in the furnace. The grate is so mounted that it can be dumped from the trough. Forward of the furnace is an auxiliary housing containing a cylindrical sifting screen into which the conveyor is extended. One portion of the screen passes the ash and another portion passes the partially burned coal. Receptacles are mounted beneath these portions. The housing has a covered opening adapted to admit an adjusted quantity of air to the usual draft opening in the forward furnace wall. A suitable shield encloses the draft path to confine the ash dust.

The invention is fully disclosed by way of example in the following description and in the accompanying drawing in which:

Figure 1 is a vertical section of a furnace equipped according to the invention;

Figure 2 is a section on the line 2—2 of Figure 1; and

Figure 3 is a section on the line 3—3 of Figure 1.

Reference to these views will now be made by use of like characters which are employed to designate corresponding parts throughout.

In Figure 1 is shown the front wall 1 of a furnace in which is mounted a grate 2. The grate is supported at one end on a journal 3 carrying a crank 4 for rocking the grate.

Beneath the grate is a concave trough 5 having flaring side wall extensions 6. In the trough is mounted a screw conveyor 6' for a purpose that will presently be described. The trough is supported on legs 7. Forward of the wall 1 is a housing 8 into and through which the shaft 9 of the conveyor is extended. The outer forward end of the shaft carries a crank 10 for rotating the conveyor.

The housing 8 contains a cylindrical screen 11 which in turn receives enlarged spiral blades 12 on the shaft 9. The top of the housing 8 has an opening 13 normally covered by a plate 14. The plate may be displaced by a suitable means such as a chain 15 for uncovering the opening 13 wholly or in part.

In the bottom of the housing 8 are two drawer

receptacles 16 and 17, both disposed under the cylindrical screen 11. The usual draft opening 18 is formed in the wall 1 beneath the trough 5. A shield or funnel 19 extends from the rear end 5 of the housing 8 to the wall 1 at an upper point over the screw 6' and at a lower point in the bottom of the opening 18 to confine the dust.

In the operation of the device, the burned coal is first dumped from the grate 2 into the trough 5, 6 by turning the grate by its crank 4. The crank 10 is then rotated to feed the material by the conveyor 6' to and into the cylindrical screen 11. The construction of the latter, by appropriately sized openings, is such that the ashes drop into the drawer 16 and the partially burned coal into the drawer 17.

The draft is created by adjusting the cover 14 to uncover the opening 13, causing a flow of air 20 through the openings 13 and 18 to the fire bed upon the grate 2. The trough 5, 6 is of insufficient width to introduce a material obstruction to the flow of air.

Although a specific embodiment of the invention has been illustrated and described, it will be 25 understood that various alterations in the details of construction may be made without departing from the spirit of the invention as indicated by the appended claims.

What I claim as my invention is:

30 1. In combination with a furnace having a grate, a trough beneath said grate, a screw conveyor in said trough, a cylindrical screen forward of said furnace, said conveyor being extended into said screen, a pair of receptacles beneath 35 said screen, a housing enclosing said screen, said housing having an opening adjacent to said screen, an adjustable cover over said opening, said furnace having a draft opening around said conveyor, and a funnel extending from an end 40 of said screen into said draft opening, whereby to conduct air from the first named opening to said draft opening.

2. In combination with a furnace having a grate, a trough beneath said grate, a screw conveyor in said trough, a cylindrical screen forward of said furnace, said screen being of larger diameter than said conveyor, blades extending from said conveyor and rotatably fitted in said screen, a pair of receptacles beneath said screen, 45 a housing enclosing said screen, said housing having an opening adjacent to said screen, an adjustable cover over said opening, said furnace having a draft opening around said conveyor, and a funnel extending from an end of said 50 screen into said draft opening, whereby to conduct air from the first named opening to said draft opening.

ALBERT DELEAN.
